UNITED STATES PATENT OFFICE.

PHILIP WUEST, JR., OF WOODBURY, NEW JERSEY, ASSIGNEE TO OSCAR BLASIUS, OF PHILADELPHIA, PENNSYLVANIA.

DEVICE FOR CENTERING MUSIC-ROLLS IN MUSICAL INSTRUMENTS.

1,041,218.

Specification of Letters Patent. Patented Oct. 15, 1912.

Application filed February 28, 1912. Serial No. 680,468.

To all whom it may concern:

Be it known that I, PHILIP WUEST, Jr., a citizen of the United States, residing at Woodbury, in the county of Gloucester and State of New Jersey, have invented certain new and useful Improvements in Devices for Centering Music-Rolls in Musical Instruments, whereof the following is a description, reference being had to the accompanying drawings and to the figures of reference marked thereon.

The invention relates more particularly to devices for centering the music rolls commonly used in automatic musical instruments.

An object of the invention is to provide devices whereby the sliding sleeves which support the trunnions for the music roll, may be simultaneously adjusted to shift the position of the center of the music roll to accommodate music sheets in which the perforations are not centralized upon the sheet itself, so that said perforations may be brought into proper register with the perforations in the tracker bar.

A further object of the invention is to provide mechanism of the above character with devices for connecting the sliding sleeves which support the trunnions of the music roll, which devices are so connected that said sleeves will be automatically adjusted to accommodate slightly varying sizes of rolls, due to expansion and contraction or other means, so that said music sheet attached to the roll may be maintained properly centered relative to the tracker bar.

These and other objects will in part be obvious, and will in part be hereinafter more fully described.

In the drawings which show by way of illustration one embodiment of the invention, Figure I, is a front elevation partly in section, showing the music roll supporting and operating devices, with my improvements applied thereto. Fig. II, is an end elevation at the right hand end of said device. Fig. III, is an end elevation at the left hand end of said device. Fig. IV, is a top plan view thereof. Fig. V, is a diagrammatic view, showing the shifting of the supports for the trunnions to accommodate different lengths of rolls, without the shifting of the center of the roll. Fig. VI, is a dia-

grammatic view showing the manner of shifting the mechanism so as to move the center of the roll relative to the tracker bar, to accommodate music sheets wherein the perforations on the sheet are off center.

It has been found in practice, that although great care is used in the forming of the music sheets, it sometimes occurs that the perforations in the music sheet are not accurately centralized upon the sheet itself. In order to bring the perforations in the sheet into proper register with the perforations in the tracker bar, some means is necessary to shift the sheet laterally so as to compensate for this non-centralized position of the perforations in the sheet.

One of the principal features of the present invention is the connecting devices which are attached to the sliding sleeves to support the trunnions, which connecting devices are so constructed that the position of said sleeves may be simultaneously and automatically shifted to bring about a re-positioning of the music sheet, to bring the perforations in the sheet into proper register with the openings in the tracker bar.

It is also found in practice that the music rolls which support the music sheet vary in length, through expansion and contraction under varying conditions, and unless some means is provided to maintain the roll centered relative to the tracker bar, this expansion or contraction of the roll will throw the perforations in the music sheet out of proper register with the perforations in the tracker bar.

A further feature of the present invention consists in so constructing these connecting devices for the sliding sleeves which support the trunnions, that said sliding sleeves will be automatically and simultaneously positioned so that slight variations in the length of the music roll, will not vary the central position of the roll.

Referring more in detail to the drawings, 1, is the usual supporting frame for the music roll and the winding roll, and also the tracker bar. The tracker bar 2, is formed with the usual perforations 3. The winding roll 4, is mounted in suitable bearings in the frame, and is operated by the usual train of mechanism so that the music sheet may be wound upon said winding roll.

The music roll 5, is provided with the usual supporting trunnions. One of these trunnions engages a sliding sleeve 6, while the other trunnion engages a sliding sleeve 7. 5 The sliding sleeves are mounted in suitable bearings 8, in the frame 1. The sleeve 7, is connected with a re-winding mechanism, so that upon proper manipulation of the controlling devices, the sheet may be re-wound 10 on the music roll. The means for operating the winding roll and the re-winding of the music roll, forms no part of the present invention, and will not need further description in this connection.

15 The sliding sleeve 6, supporting the trunnion at one end of the music roll 5, is connected to a rod 9, which projects through the supporting bearing 8, and is provided with a limiting collar 10. Said bar projects beyond the limiting collar and is formed with a rounded end 11. The sleeve 7, at the other end of the music roll projects through the bearing 8, and the operating devices for re-winding the roll, and is provided with a rounded end 12. A limiting collar 13, is also secured to said roll.

Mounted in a bracket 14, secured to the frame 1, is a rock shaft 15. Said rock shaft carries a downwardly projecting arm 16, which is formed with a flat end adapted to bear against the rounded end 11, of the rod 9. Said rock shaft is also provided with a second downwardly projecting arm 17, which is connected to one end of a coil spring 18, the other end of the spring being connected to an adjustable link, shown in dotted lines at 19, in Fig. I. At the other end of the device is a bracket 20, which is provided with a rock shaft 21. Said rock shaft carries a downwardly projecting arm 22, which has a flat end adapted to bear against the rounded end 12, of the rod connected with the sliding sleeve 7. Said rock shaft 21, is formed with an upwardly projecting arm 23. The rock shaft 15, is also provided with an upwardly projecting arm 24. On the bracket 25, intermediate the ends of the frame, is a swinging lever 26, which is fulcrumed at 27, to said bracket. 50 This lever 26, is connected to one end of a link 28, which link at its other end is pivotally connected to the upwardly projecting arm 24, of the rock shaft 15. The other end of the lever 26, is pivoted to one end of a link 29, which link in turn is pivoted at its other end to the upwardly projecting arm 23, on the rock shaft 21.

From the above description, it will be apparent that I have provided a series of 60 levers and links which connect one sliding sleeve to the other sliding sleeve, and these levers and links are so disposed that the outward movement of one sleeve will cause a corresponding outward movement of the other sleeve.

Referring to the diagrammatic view in Fig. V, it will be apparent that if the roll 5, should expand as indicated in dotted lines, the sliding sleeve 6, will move outward, causing the rock shaft 15, to swing 70 and through the link 28, swing the lever 26, about its fulcrum, to the dotted line position, which through the link 29, will swing the rock shaft 21, so as to move the sleeve 7, to a corresponding degree, and in the opposite direction. If the roll is contracted or shortened in any way, there will be a similar movement of the sleeves 7, and 6, toward each other. The coil spring 18, operates to permit a yielding movement of both of the sliding sleeves outward or inward to accommodate varying lengths of rolls, or to allow the removal and insertion of a roll, and when said sliding sleeves engage the trunnions of the roll, said roll will be centered relative to the tracker bar. From this construction, it will be apparent that even if the music rolls vary in length slightly through any reason, the music sheet which is properly centered on the roll, will still be maintained properly centered relative to the perforations in the tracker bar. This means above described, not only provides a positive means for properly supporting varying sizes of music rolls, but also allows the music roll to be readily removed or inserted between the sliding sleeves. 90

In order that the center of the music roll relative to the tracker bar may be shifted, I have formed the link 29, in two sections 30, and 31. These two sections have spaced ends located adjacent each other, which are formed with right and left hand threads. A sleeve 32, is formed with similar threads, and engages the ends of the sections 30, and 31. This sleeve 32, joins the sections of the link 29, and said link 29, will move bodily endwise for the purpose above stated. By turning the sleeve 32, the link 29, may be lengthened or shortened. 105

Referring more particularly to the diagrammatic view in Fig. VI, it will be apparent that if the link 29, is lengthened, the lever 26, will be moved to the dotted line position in said figure, and the rock shaft 21, will be moved in an opposite direction, as indicated in dotted lines in said figure. This movement of the lever 26, will, through the link 28, impart a movement to the rock shaft 15, which movement will swing the 115 arm 16, in the same direction as the arm 22, and therefore, the entire music roll will be shifted endwise, as indicated in dotted lines in this figure. If the link 29, is shortened instead of lengthened, the music roll 5, 120 would be shifted endwise in an opposite direction. It will be apparent therefore, that through this adjustment of the link 29, I may shift the center of the music roll relative to the tracker bar. If a music sheet 125

therefore, is attached to the music roll, which music sheet has the perforations formed therein which are not centralized on the sheet itself; said roll with the sheet attached, may be shifted relative to the center of the tracker bar, to properly centralize the sheet, and bring the perforations therein into proper register with the perforations of the tracker bar.

10 In order to facilitate the lengthening or shortening of the link 29, that is, the turning of the sleeve 32, I have provided said sleeve with a sprocket wheel 33. A short shaft 34, is mounted in the frame 1, and carries a sprocket wheel 35, on its outer end, which is connected through the chain 36, with the sprocket wheel 33. Said short shaft 34, is provided with a thumb wheel 37, which extends within the side member 20 of the frame, to a point adjacent the end of the music roll, so that said thumb wheel is readily accessible for turning. The turning of this thumb wheel, through the sprocket wheels and the connecting chains, will rotate the sleeve 32, in one direction or the other, to shift the center of the music roll. In order that the amount of the shifting of the music roll may be indicated, and said sliding sleeves may be brought back to normal position, for a normal roll, I have provided an indicator pointer 38, which is mounted on a sliding bar 39, and said pointer co-operates with an indicating mark 40, which determines the normal position of the parts for the normal roll. This sliding bar 39, is pivoted to a depending arm 41, which in turn is pivoted at 42, to the bracket 25 21, and is pivotally connected with a threaded nut 43.

40 The nut 43, engages a thread on the short shaft 44, so that as said shaft is rotated to vary the position of the sleeve 32, the nut 43, which is held from turning through its pivotal connection with the arm 41, will be moved longitudinally of the short shaft, and thereby impart a longitudinal movement to the bar 39, and a movement of the pointer 38, relative to the indicating mark 40.

45 In the operation of my device, the sliding sleeves are moved away from each other, either by the movement of one sleeve or the other, and the roll inserted between said sliding sleeves. These sleeves as above noted, will position themselves automatically and simultaneously, so as to hold the roll properly centralized relative to the tracker bar. When it is desired to shift the roll endwise, the thumb wheel 37, is rotated and through the connecting mechanism, sleeve 32, is rotated, thus lengthening or shortening the link 29, and causing the music roll to move bodily endwise, in accordance with the adjustment of the link 29, and therefore, a shifting of the center of the roll relative to the center of the tracker bar. The

pointer 38, will indicate the amount of shift and will enable the operator to readily bring the parts back to normal position for the normal music roll and music sheet wherein the perforations are properly centralized on said music sheet.

70 It is obvious that minor changes in the details of construction and arrangement of parts may be made, without departing from the spirit of the invention as set forth in the appended claims.

75 Having thus described my invention, I claim:

1. The combination with a tracker bar, of members for engaging the trunnions of the 80 music roll for supporting the same, means whereby the shifting of one supporting member moves the other supporting member in the opposite direction, and means whereby said supporting members may be simultaneously shifted in the same direction.

2. The combination with a tracker bar, of members for engaging the trunnions of the music roll for supporting the same, devices 90 for connecting said supporting members, whereby the shifting of one member moves the other member in the opposite direction, and devices whereby said supporting members may be shifted in the same direction.

3. The combination of a tracker bar, of 95 members for supporting the music roll, devices for connecting said members whereby the shifting of one member in one direction causes a shifting of the other member in the opposite direction, yielding means for holding said members in contact with the music roll, and means for shifting said members simultaneously in the same direction, for centering the music sheet relative to the 100 tracker bar.

105 4. The combination with a tracker bar, of sliding sleeves for engaging the trunnions of the music roll for supporting the same, devices connecting said sliding sleeves whereby the shifting of one sleeve moves 110 the other sleeve in the opposite direction, and devices whereby said sleeves may be shifted in the same direction.

5. The combination with a tracker bar, 115 freely sliding members for engaging the trunnions of the music roll, a rock shaft having an arm for engaging each sliding member, devices for connecting said rock shafts whereby the movement of one sliding member imparts a movement in the opposite 120 direction to the other sliding member, said devices including means whereby said sliding members may be simultaneously moved in the same direction.

6. The combination with a tracker bar, of 125 sliding members for engaging the trunnions of a music roll, a rock shaft having an arm engaging each of the sliding members, a lever fulcrumed intermediate its ends, a link connecting the ends of the lever with the re- 130

spective rock shafts, and means whereby one of said links may be lengthened or shortened.

7. The combination with a tracker bar, of 5 sliding members for engaging the trunnions of a music roll, a rock shaft having an arm engaging each of the sliding members, a lever fulcrumed intermediate its ends, a link connecting the ends of the lever with the 10 respective rock shafts, means whereby one of said links may be lengthened or short-

ened, said means including a thumb wheel, and a pointer for indicating the amount of shift of said sliding members.

In testimony whereof, I have hereunto signed my name at Philadelphia, Pennsylvania, this twenty-seventh day of February, 1912.

PHILIP WUEST, JR.
